BURIAL VAULT LOCKING MECHANISM

Charles J. King, Galion, Ohio, assignor to Perfection Steel Body Company, Galion, Ohio, a corporation

Application June 14, 1935, Serial No. 26,680

2 Claims. (Cl. 292—48)

The purpose of the present invention has been to produce a simple, compact, and efficient locking mechanism particularly designed for application to metal burial vaults, for locking the vault body in place upon the base provided therefor in these constructions of vaults.

An especial object in the provision of the mechanism of the invention lies in the arrangement and formation of the parts such as permits of a very quick assemblage of the various parts in place upon the base of the vault ready for locking cooperation with the vault body, the method of assembly being such as does away with connecting cotterpins or other fastening devices between the operating lever for the locking dogs, and the means for adjusting the locking parts to maintain their locking and unlocking positions being simple and readily operable according to the invention.

A novel feature of the operating means for the locking parts lies in the provision of an auxiliary handle capable of being actuated when the vault is standing on end and the main operating handle is not in a convenient position for the actuation of the lock members or dogs that connect the vault body and base in locked relation. The auxiliary operating means for the locking mechanism is located underneath and within the base structure, which is usually of hollow formation and therefore permits the mounting of the auxiliary handle or actuating part in the location stated.

For a full understanding of the invention a preferred embodiment thereof is described herein and shown in the accompanying drawings, in which—

Figure 1 is a top plan view of the end portion of the vault base looking down thereon and illustrating the lock means of the invention.

Figure 2 is an end view of the same.

Figure 3 is a sectional view at right angles to Figure 4, showing more fully the arrangement of the pivot lever for actuation of the pull rods connected to the locking dogs, the enclosure of the lever and pull rod devices by the cover plate, and the disposition of the cam handle and auxiliary handle, the top or body of the vault being partially shown and broken away.

Figure 4 is a fragmentary view in side elevation of certain of the lock mechanism features.

Figure 5 is a sectional view bringing out more clearly the construction of one of the locking dogs.

Figure 6 is a detail view of one of the pull rods.

Figure 7 is a detail view of the other pull rod.

Figure 8 is a view in elevation of the cover plate

which cooperates with an end portion of the base to house the locking mechanism.

Figure 9 is a fragmentary end view of the vault base, illustrating the operating instrumentalities through which the locking dogs are actuated.

Referring to Figures 1 and 3 of the drawings, it is notable that the base of the type of metal burial vault of the invention consists of a plate 1 which is formed at its edges with a relatively vertical downwardly projecting side flange 2. This side flange is bent at its lower edge in an outward direction and slightly upwardly to form a pan or vault body receiving flange 3. Upon this flange the lower edges of the vault body 4, which are in-turned and bent upwardly as shown at 5 and 6, are received when the body is disposed over the base 1 as when in closed condition for shipment or after a casket has been disposed in the vault ready to be lowered into a grave.

The locking mechanism of the invention is duplicated at the opposite ends of the base and therefore the mechanism at one end only will be described and will make clear the particular novel features of the invention.

The vault body and base as previously set forth are of the conventional construction at present in use. At the sides of the base and in the vertical flange 2 thereof, near each end, are located the outwardly swinging pivoted dogs 7. These dogs are hung upon pintle rods or pivot members 8 and swing outwardly through suitable slots in said side flange or skirt portion 2 of the base. For the operation of the rods of the dogs 7 simultaneously to withdraw them so that they do not project outwardly from the portion 2 of the base as shown in Figure 2, there is provided a lever 9 pivoted intermediate its ends as at 10. The upper end of the lever 9 is connected by a pull rod 11 with the lower actuating extension 1a of the dog 7. The pull rod 11 is shown best in Figure 7, having the inwardly bent end 11b to coact with the dog 7 with which it directly cooperates. The lower end of the lever 9 is connected by another pull rod 12 shown best in Figure 6, and the pull rod 12 leads from said lever 9 to the other one of the dogs 7, that opposite the one which is operated by the pull rod 11. The pull rod 12, however, is made slightly different from the rod 11 in that the rod 12 has a laterally bent end 12a to coact with the dog 7 which it works, and an opposite laterally bent end 12b to cooperate with the lever 9 by passing through the lower end thereof. The end 12b of the rod 12 is longer than the end 12a so that it may not only pass through the lower end of the lever 9.

sufficiently to make connection with the lever, but it additionally passes through a cover plate 13 beneath the base near the end at which the locking mechanism described is located. The cover plate 13 has a main, approximately vertically disposed body, spaced in parallel relation with the adjacent skirt or flange 2 of the base, and at the bottom edge of the plate 13 is a laterally outwardly bent flange 14 to close said space. 5

10 Thus the plate 13 and its base flange 14 form an effective covering means for certain of the pull rods and lever parts described. Said cover plate may be welded in place, as will be later set forth.

15 The end 12b of the pull rod 12 projects sufficiently far inwardly to the hollow portion of the base 1, from the plate 13, to provide an auxiliary handle for use as hereinafter explained. There are provided for the dogs 7, as seen best in Figure 5, flat springs 15, one end of each spring engaging a flat side of the hollow portion of the dog 7, being curved over the pintle rod or pivot 8 for the dog and engaged beneath the base 1 as seen in said figure. Normally the action of 20 the spring is to push the dog 7 to its working position, that position in which it is projected outwardly through the slot 16 of the skirt or flange 2 whereby to cooperate with the portion 6 of the body or top of the vault and lock the latter down on the base.

25 Since the movement of the pull rod 12 by the lever 9 is necessary for actuation of the cooperating dogs 7, the opening in the cover plate 13 to which the auxiliary handle 12b passes is of arc-shaped form, as shown at 17 in Figure 8 where said opening is clearly illustrated. The said end 12b moves on an arc about the axis 10 of the lever 9 and therefore the opening 17 is formed on the same arc, for obvious reasons.

30 As a main actuating means for operating the locking parts 7 at each end of the vault I employ a main handle 18 as seen in Figures 4 and 2, said handle being a part of a U-shaped member, the intermediate portion of which is a shaft 19 and the innermost portion of which is an arm 20. 35 The arm 20 is adapted to abut with the lower end portion of the lever 9 to rock said lever in such a manner that the connected ends of the pull rods 11 and 12 are pulled upon and the dogs 7 are withdrawn into the hollow portion of the base 1. 40 At such time the arm 20 of the operating member, which comprises the handle 18, assumes the position illustrated in Figure 9. In other words, the upper end of said arm 20 so engages the lower edge of the lever 9 as to abut with the same in a manner to hold the lever locked with the dogs 7 withdrawn into the base. At such time the actuating member 18 will have reached a horizontal position at the limit of its movement in one direction, as shown in said Figure 9. The intermediate shaft portion of the member 19 of the actuating member 18 for the lever 9 is held in place on the adjacent part 3 of the base by means of a bearing sleeve 21 welded to the part 3. The part 3 at its outer up-cupped edge is cut away opposite the location of the actuating member 18 so that the latter may be depressed by stepping upon the same with the foot, or by use of the hand, and the said outwardly up-turned portion of the base flange 3 will not interfere with such movement. The cut away portion aforesaid of the part 3 is designated 22. 45

50 The axis 10 of the lever 9, shown best in Figure 3, comprises a bolt 23, the head of which is outermost and the square portion 23a of which passes

through a square hole in the skirt or flange 2. The inner portion of the bolt passes through the lever 9 and a nut 24 is then screwed upon the bolt.

5 In assembling the parts, the lever 9 is engaged with the ends 11a and 12b of the rods 11 and 12 after the bolt is passed through the part 2. Then the nut 24 is screwed on the bolt and holds the lever 9 in place and similarly holds the parts of the rods 11 and 12 engaged by the lever from being displaced therefrom. Cotterpins are thus dispensed with. The parts so assembled, the handle 18 and its integral portions 19 and 20 are placed in position on the member 3 and the sleeve 21 is welded to the part 3 to provide the bearing for the part 19. Thereupon cover plate 13 is placed in position and may be welded or otherwise secured so as to enclose the parts 9, 11, 12, and 24. 10

15 When the handle 18 is raised from the position of Figure 9, the lever 9 is unlocked and the springs 15 thereupon force the dogs 7 outwardly and the vault body is thus locked to the base. 20

25 When the vault with its body and base are in standing position, as for instance standing on one end, the operation of the locking dogs 7 to operate the two may be performed by the grasping of the auxiliary handle 12b from a point at the bottom of the base, thereby to release the dogs 7 by withdrawal into the base in a self-evident manner. 30

35 Summarizing the assembly of the mechanism as above described, after the bolt 23 has been passed through the square hole in the skirt or flange 2 of the base, the lever 9 is placed in position on the bolt with the members 11 and 12 having their end extensions 11a and 12b passed through the end openings of the lever in a direction away from the said skirt 2. Thereupon, when the nut 24 is screwed in place, parts 11 and 12 will be held from displacement from the lever 40 by being supported between the lever and skirt 2. No cotterpins are required for this assembly of these parts. Next the handle unit 18, 19, 20 is slipped through a hole near the lower edge of the skirt 2 as shown, the part 20 arranged properly in 45 relation to the lever and the sleeve bearing 21 welded to the flange 3 over the portion 19 of the main handle unit. The hinge pins of the locking dogs 7 are placed through holes in said dogs and the springs 15 are placed in position coacting with 50 the dogs and extending over the hinge pins 8; then the outer ends of the pull rods 11 and 12 are inserted in the holes in the lower extended portions of the dogs 7 and the pins are then welded 55 at the angle of the base plate 1 and the skirt 2 underneath the same.

60 The cover plate 13 is now placed in position and welded to the parts 1 and 2, thereby completing the installation of the locking mechanism upon 65 the base of the vault. As previously stated, when the vault is flat upon the ground or in horizontal position, the locking mechanism may be unlocked by simply pressing down on the member 18 with the foot to carry said member 18 to the position of Figure 9. Lifting of the member 18 will free the locking dogs and permit their automatic engagement with the vault cover or body when the latter is deposited upon the base. When the 70 vaults are standing on end so that it is not easy to operate the member 18, the unlocking action of the dogs 7 may be effected by the auxiliary handle 12b. 75

Having thus described my invention, what I 75

claim as new and desire to secure by Letters Patent of the United States, is—

1. Locking means for use on a grave vault base plate, comprising a lever adapted to be mounted on a skirt portion of a base, locking dogs having portions movable through the skirt portion of the base to engage with a cover for the vault, pull rods connected each at one end to the lever and at the opposite end thereof to one of the locking dogs, a handle unit pivoted to the base plate and extending outwardly therefrom, said unit including a main handle, a pivot portion adapted to extend through the base, and a lever impinging arm on said pivot portion disposed in the same plane as the said lever to engage the lever for operating the pull rods to withdraw the dogs from their locking positions, the inner end of one of the pull rods being projected from the base at its point of connection with said lever to provide an auxiliary handle adapted to be used when the main handle is inaccessible or not easy of operation.
2. Locking means for use on a grave vault base plate, comprising a lever adapted to be mounted on a skirt portion of a base, locking dogs having

portions movable through the skirt portion of the base to engage with a cover for the vault, pull rods connected each at one end to the lever and at the opposite end thereof to one of the locking dogs, a handle unit pivoted to the base plate and extending outwardly therefrom, said unit including a main handle, a pivot portion adapted to extend through the base, and a lever impinging arm on said pivot portion disposed in the same plane as the said lever to engage the lever for operating the pull rods to withdraw the dogs from their locking positions, the inner end of one of the pull rods being projected from the base at its point of connection with said lever to provide an auxiliary handle adapted to be used when the main handle is inaccessible or not easy of operation, said handle unit main handle being located exterior to the base, and the auxiliary handle member located underneath the base, and the said lever impinging arm having a square end for abutment with the lever at a predetermined point in the rocking of the latter to give a self-locking effect for holding the lever in a position maintaining the dogs unlocked.

CHARLES J. KING. 25
